UNITED STATES PATENT OFFICE.

FREDERICK G. KEYES, OF EAST ORANGE, NEW JERSEY, ASSIGNOR TO COOPER HEWITT ELECTRIC COMPANY, OF HOBOKEN, NEW JERSEY, A CORPORATION OF NEW JERSEY.

ELECTRIC LAMP.

1,270,843.

Specification of Letters Patent.

Patented July 2, 1918.

Application filed June 26, 1914. Serial No. 847,403.

To all whom it may concern:

Be it known that I, FREDERICK G. KEYES, a citizen of the United States, and resident of East Orange, county of Essex, State of New Jersey, have invented certain new and useful Improvements in Electric Lamps, of which the following is a specification.

An important feature of the heavy tungsten filament lamp made known by me, for example, in my application No. 811,902, filed January 8th, 1914, is that of adequately supporting the filament and at the same time furnishing a convenient means for making connections inside the lamp. The disk which I have employed is generally of aluminum and the anchor rods for the tungsten wire are supported by but insulated from this disk.

These and other details of my invention are clearly shown in the accompanying drawings in which Figure 1 is a vertical section of one of my electrodes, a portion of which is shown in full lines; Fig. 2 is a detail of a connection to the filament terminals; Fig. 3 is a side view of the aluminum disk and Fig. 4 is a plan of the suspended filament.

Where filaments of the nature herein described are used, it is better not to attempt to maintain the filaments in mere straight lines or regular curves. It is preferable to allow a certain amount of sagging, and support the filaments in such a way as to provide for such a sagging, at the same time guarding against the touching and consequent short circuiting of adjacent parts of the filament.

In the present instance the filament shown at 1 falls into what I may call a basket shape or bowl shape. The filament is contained within a globe, 2, and is wound spirally from end to end but allowed to sag as already described. At its ends the filament is attached to lead wires, 3, 3, say of iron tipped with tungsten, and the connection is made with each terminal by making the lower end, 4, of the lead bulb-shaped and winding around it a portion of the exposed end of the tungsten spiral and then applying an oxy-acetylene flame adding, if necessary, a small amount of iron as shown at 5. Since iron welds to tungsten very readily a secure electrical connection is made.

The globe 2 is provided with a reduced tubular extension, 6. Near where the exten-

sign begins, a disk, 7, of aluminum is placed being itself supported intermediately from a reentrant portion, 8, of the chamber formed by the outer end of the extension. To such reentrant portion is attached an arbor, 9, of the same material as the wall of the container or its extension and usually integral therewith. The arbor is provided with an upset portion, 10, while the disk has a sleeve, 11, with a split expanded portion, 12, the latter being adapted to cover and engage the upset portion of the arbor. The disk with its sleeve may be passed over the arbor and the engagement of the expanded portion of the sleeve with the upset portion of the arbor having taken place the whole may be firmly fixed in position by means of a wire, 13, securely twisted around the fingers of the split expanded portion.

The end of the arbor, 9, has attached to it in any suitable manner anchor wires, 14, 14, which extend into such a position below the tungsten filament 1 that loops made in the ends of the wires may engage and hold up different portions of the tungsten filament without requiring that the filament should be maintained rigidly in a straight or continuously curved line. The anchor wires may be mainly nickel steel rods provided with tip portions, 15, 15, of tungsten or other refractory metal in the form of wire. Besides the rods 14, 14, which, having been secured to the end of the arbor 9 are naturally insulated from each other, there are anchor wires, 16, 16, which have the same general construction as the anchor wires 14, 14, which extend upward through insulating blocks 17, 17, in the disk 7. In a similar way the lead rods, or wires, 3, 3, are insulated from each other and from the disk 7 by means of insulating sleeves in the disk 7. Above the disk 7 the leads 3, 3 are secured, by silver soldering or by any approved method which insures electrical connection, to leading-in conductors, 18, 18, 100 passing through and forming a part of the seals 19, 19, of the lamp. The details of these seals form no part of the present invention and need not be further described. The sleeves may be connected to the external circuit by means of wires, 20, 20 and soldered to the ends of the sleeves.

I claim as my invention:

1. In a tungsten filament lamp, a container, a heavy filament therein, an exten-

sion of the container and supporting means for the said filament comprising a nonconducting depending arbor centrally disposed within the extension, anchor wires for connection with different parts of the filament and an insulated metal disk and sleeve surrounding the said arbor.

2. In a tungsten filament lamp, a container, a heavy filament therein, an extension of the container and supporting means for the said filament comprising a nonconducting depending arbor centrally disposed within the extension, anchor wires for connection with different parts of the filament and an insulated metal disk and sleeve surrounding the said arbor, the terminals of the filament being connected to the lamp seals by insulated rods extending through the disk.
3. In a tungsten filament lamp, a container, a heavy filament therein, an extension

of the container and supporting means for the said filament comprising a nonconducting depending arbor centrally disposed within the extension, the said arbor having 25 an upset portion, and an insulated supporting metal disk carrying a sleeve adapted to engage said upset portion.

4. Supporting means for heavy tungsten filaments comprising a non-conducting arbor 30 having an upset portion, an insulated supporting disk carrying a sleeve adapted to engage the said upset portion and means for binding the upper end of the sleeve to the arbor above the upset portion. 35

Signed at New York, in the county of New York and State of New York this 25 day of June, A. D. 1914.

FREDERICK G. KEYES.
